UNITED STATES PATENT OFFICE.

WILLIAM P. KILLEEN, OF WASHINGTON, DISTRICT OF COLUMBIA.

CONCRETE FLOOR CONSTRUCTION.

1,264,089.

Specification of Letters Patent. Patented Apr. 23, 1918.

Application filed September 13, 1917. Serial No. 191,215.

To all whom it may concern:

Be it known that I, WILLIAM P. KILLEEN, a citizen of the United States, and resident of Washington, in the District of Columbia, 5 have invented new and useful Improvements in Concrete Floor Constructions, of which the following is a specification.

This invention relates to concrete floor construction and more particularly to a 10 sleeper tie, which is used in the construction of concrete buildings.

The invention resides in a sleeper tie which is exceedingly durable, cheap and easy to manufacture and the using of the tie results 15 in a great saving of time and labor.

From practical experiments it is to be found that the use of the invention materially cheapens the cost of reinforced concrete floorings.

20 The invention further provides suitable means whereby the floor sleepers are arranged in the upper portion of the concrete flooring to serve the purpose of guides for the top surface of the flooring, and to provide means for securing the wooden flooring 25 to the concrete construction.

The above and other objects and advantages of my improvement will fully appear from the following description taken in connection with the accompanying drawing and 30 be explicitly defined in the appended claim. I wish it understood, however, that this disclosure is illustrative only, and that the principle of my invention can be embodied in 35 constructions other than the one specified herein.

In the drawings,

Figure 1 is a plan view of the sleeper tie; Fig. 2 is a side view of the same;

40 Fig. 3 is a vertical sectional view through the concrete foundation;

Fig. 4 is a similar view showing a modified form of the sleeper tie;

Fig. 5 is a top view of the structure shown 45 in Fig. 3;

Fig. 6 is a top view of the structure shown in Fig. 4;

Fig. 7 is a view showing modified form of 50 sleeper tie; and

Fig. 8 is a perspective view, showing how the sleeper tie secures the sleeper to the foundation.

55 Referring to the drawings, the numeral 10 shows a sleeper tie which is preferably made of cheap, durable material, such as sheet metal or wire. Obviously, the tie can be

stamped with a machine, cut by hand or made in other ways. Midway the length of said sleeper tie is shown a foundation or anchoring area 11, said area comprising four 60 tongues 12, 13, 14, and 15. The object of this area is to enable the tie 10 to be securely held and anchored in the concrete, as will be more fully described later.

The metal tie 10 is embedded in concrete 65 before the concrete has become solidified. At the level 17, two ends of the tie will project above. These ends may be bent parallel with the level 17 until used, the purpose of this bending being to prevent any one tripping or to prevent the ends from being broken off. When it is desired to secure the sleeper 18 to the concrete floor, the sleeper 18 is placed between the ends of the tie. The ends of the tie are then bent to conform to 75 the shape of the sleeper and may be secured to said sleeper by several different means. Fig. 3 shows the metal ends nailed or otherwise secured to the sleeper. Fig. 4 shows, in addition to the ends of the tie being secured to the sleeper, another securing means. The additional securing means resides in the extreme ends of the tie being bent, to extend outwardly from said sleeper into the cinder 80 filler 20.

Instead of the means of securing the tie to the sleeper as shown in Figs. 3 and 4, I have shown means of accomplishing this result by another modified form as shown in Fig. 7. In this figure, the metal tie is of 90 greater length than the tie shown in Fig. 3 and the extreme ends extend around the sleeper and are secured to the top thereof by nails, screws or other securing means. It will be seen that in this last form, the tie 95 completely surrounds the sleeper and firmly holds the sleeper in place, but the disadvantage of this form is that the tie may be observed.

It is believed from the above description 100 and operation that the construction of the invention is apparent. It is obvious that many modifications may be resorted to without departing from the spirit of the invention. For example, the shape of the several 105 tongues 12 to 15 may be widely varied and any configuration of the tongues or foundation area would suffice if the tie could be firmly intrenched in the concrete.

In reduction to practice, I have found that 110 the form of my invention illustrated in the drawings and referred to in the above de-

scription as the preferred embodiment is the most efficient and practical, yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention as defined in the appended claim.

Having thus fully described my invention what I claim and desire to secure by Letters Patent, is:

The combination with a sleeper having

beveled sides disposed on a bed of concrete, of a sleeper tie comprising an elongated metal strip having formed intermediate its ends a plurality of radially extending tongues, each of the tongues being embedded in said bed of concrete, the ends of each tie being adapted to project upwardly through said concrete, fastening means securing said ends to the beveled sides of the sleeper, and means provided at the ends of the tie serving as an auxiliary anchor for securing said parts in position.

WILLIAM P. KILLEEN.
